Geo. P. Kimmel. Attorney

UNITED STATES PATENT OFFICE.

ARTHUR D. HULLETT, OF NEWPORT, TENNESSEE.

WRENCH.

1,399,621.

Specification of Letters Patent.

Patented Dec. 6, 1921.

Application filed February 23, 1921. Serial No. 447,023.

To all whom it may concern:

Be it known that I, ARTHUR D. HULLETT, a citizen of the United States, residing at Newport, in the county of Cocke and State 5 of Tennessee, have invented certain new and useful Improvements in Wrenches, of which the following is a specification.

This invention relates to socket wrench handles and more particularly to that class 10 of tools adapted to receive various size, removable sockets for engagement with different size nuts whereby the same may be tightened or removed from a part.

The primary object of the invention is 15 the construction of a socket receiving implement or tool whereby provision is had to turn the socket either to the left or right in tightening or removing threaded nuts or other fastening element without removing 20 the implement from the part being turned.

A still further object of the invention resides in the provision of a socket receiving implement for accommodating various 25 size socket heads whereby the same may be actuated to loosen or tighten nuts, caps or other fastening elements, including spring controlled dogs whereby the implement may be operated either to the left or right without 30 removing the same or the socket head from the part being turned.

Another and very important object of the invention will be found to reside in the provision of a socket receiving implement 35 which will be extremely simple in construction, positive in operation, consisting of comparatively few parts and therefore inexpensive to manufacture, rigid and durable in use, highly efficient in performing its 40 functions and of universal application for various uses in the different trades.

With these objects in view and others which will be manifest and suggested as the nature and purpose of my invention are 45 revealed in the following specification and drawing wherein I have shown a practical, yet preferred embodiment thereof.

Figure 1 is a plan of the implement.

Fig. 2 is a bottom view thereof with the 50 handle broken away.

Fig. 3 is a side view, and

Fig. 4 is a sectional view taken on the line 4—4 of Fig. 2.

Referring now to the drawings wherein 55 like parts designate similar and corresponding parts in the specification, 5 designates

the wrench stock or handle which may be flat or of any desirable shape, and terminates in a forward, enlarged head 6 which is preferably rounded at 7 to conform with 60 the shape of a ratchet mechanism subsequently to be described. The enlarged head 6 is provided with an aperture near its outer end designated by numeral 8 and is adapted to receive the rounded portion 9 65 which constitutes a pivot or bearing surface of a polygonal shape element 10 carried thereby for the reception of the removable sockets which are adapted to be engaged therewith for turning the fastening element 70 above referred to.

Formed integral with or separable from the pivot member, I have provided a ratchet 11 formed with ratchet teeth 12 thereon, said ratchet lying at the outer or end of 75 the head 6 and of course conforms to the rounded shape thereof. Another ratchet member 13 having ratchet teeth 14 thereon is also retained and operable with the pivot member 10 and lies flush and contiguous 80 with the bottom of said enlarged head, as clearly shown in Fig. 3 of the drawing. Any suitable form of fastening means such as a set screw 15^a may be provided for securing the said lower ratchet member on the central 85 pivot member.

The head 6 also carries a pair of double toothed, pawls 15, 16 each of which is provided with extended teeth 17, 18 for engagement with the respective teeth of the 90 ratchet members above referred to. The said pawls 15, 16 are pivotally retained on a transverse pin 19 extending through the head 6 and as shown have fastening pins 21 whereby the respective pawls are retained 95 and both operable upon rotation of the transverse pin 19. Of course, both of the pawls are adapted to be operated at the same time so that the respective teeth 17, 18 may engage the ratchet members when it is desired to operate the wrench either to the 100 left or right. A transverse stud 20 having a shoulder 21^a and a knurled head 22 is positioned in proximity to the head 16 and is provided with a groove or recess 23 for 105 the reception of a resilient spring member 24 adapted to overlie the same, one end of the spring being secured in a recess 25 of one of the pawls and the opposite end of the said spring being made fast and secure 110 in a recess 26 in the stock or handle of the wrench. The resiliency of the spring is

such as to permit the same to be removed from the groove 23 and is of course adapted to be thrown to the other side of the stud and upon such movement will cause the 5 tooth 17 or the tooth 18 as the case may be, to engage the teeth of the ratchet mechanism above referred to. In other words the movement of the spring 24 either to the right or left of the stud will oscillate the 10 transverse pivot 19 carrying the respective pawls so that they will engage with the ratchet members 11 and 13 whereby the stock carried by the member 10 may be operated either to the left or right as desired. 15 If so desired, the member 10 may be constructed with a polygonal, or similar shaped internal socket so that it may also engage a cap or screw threaded element to tighten or remove the same in the same manner as 20 the removable stocks above referred to.

In the accompanying drawings, I have illustrated my invention embodied in one form by way of example, and which in practice has been found to be highly satisfactory 25 in obtaining the desired results. It will be obvious however that other embodiments may be adopted and that various changes in the details of construction may be resorted to by those skilled in the art without de- 30 parting from the spirit and scope of the invention. It is furthermore understood that the invention is not necessarily limited or restricted to the precise elements shown ex- 35 cept in so far as such limitations are specified in the subject matter being claimed.

Having shown and described my invention what I now claim as new and desire to

secure by Letters Patent of the United States is:—

1. In a wrench, the combination with a 40 handle having an enlarged head, a nut receiving element rotatably carried by said head, a ratchet member integral with said rotatable element, a separable ratchet member carried by and rotatable with said first 45 mentioned ratchet member, double toothed pawls pivotally secured in said head for simultaneous engagement with the ratchet members, and spring controlled means secured to one side of the handle and to one 50 of said pawls for simultaneously oscillating the same for engagement with the ratchet members whereby the rotating element may be operated to the left or right.

2. In a wrench, the combination with a 55 handle having an enlarged head, a nut receiving element rotatably carried by said head, a ratchet member rotatable with said nut receiving element, a separable ratchet member also carried by said rotating element 60 and operable therewith, a pair of similar, double toothed pawls pivotally secured on each side of said head and engageable simultaneously with the ratchet members, a stud removably secured in proximity to one of 65 said pawls, a spring fastened to said handle and retained by one of said pawls loosely overlying said stud whereby said pawls may be oscillated by the movement of said spring and permit the ratchet teeth and rotating element to operate either to the left or right. 70

In testimony whereof, I affix my signature hereto.

ARTHUR D. HULLETT.
